ARTHUR P. HAHNEL, OF ROYERSFORD, PENNSYLVANIA, ASSIGNOR TO RISING SUN EMBROIDERY WORKS, INC., OF ROYERSFORD, PENNSYLVANIA

STOCKING FRAME FOR EMBROIDERING MACHINES

Application filed August 16, 1932. Serial No. 628,977.

This invention relates to an embroidering frame for embroidering machines and has for its primary object the provision of a simplified type of frame which is capable of an increased number of adjustments to enable the front, rear and sides of the stocking to be embroidered.

A feature of the invention resides in the design of the frame so that the same may be adjusted to either one of four positions to enable the embroidering of four designs on a stocking in counter distinction to the embroidering of two designs which is the trade method usually employed.

15 A feature of my invention resides in the provision of a pair of spaced rings arranged in spaced relation by strips that coat with the rings to define slots through which the embroidery needles operate in performing their embroidering operation.

Besides the above my invention is distinguished in the novel manner of clamping the upper portion of the stocking in place and holding the same taut over the various slots.

25 My invention is also distinguished in the use of an annular support coacting with a ring of the frame in a manner to enable the frame to be rotated to various cooperative positions in relation to the embroidery needles of the machine.

With these and other objects in view the invention will be better understood from the following detailed description taken in connection with the accompanying drawing, 35 wherein:

Figure 1 is a side elevation of the frame.

Figure 2 is a vertical sectional view.

Figure 3 is a horizontal sectional view.

40 Figure 4 is a detail sectional view of a portion of the upper ring.

Again referring to the drawing illustrating one of the many constructions of my invention the numeral 1 designates an annular support provided with an attaching lug 2 by means of which the support may be attached to the embroidering machine. Rotatably mounted on this support 1 is the lower ring 3 of the frame, the upper ring of which is arranged in spaced relation with the ring 50 3 through the use of strips 5 that are arranged

in equal spaced relation to provide slots 6 through which the needles of the embroidering machine operate in the embroidering of the stocking stretched over the slots.

The lower ring 3 is provided with recesses 55 7 adapted to be selectively moved into engagement with a clamping device illustrated as a thumb screw 8. Attention is called to the fact that the recesses are aligned with the slots and are equally numbered so that the frame is capable of four adjustments to selectively move the slots in cooperative relation with the needles of the embroidering machine.

Projected obliquely from the ring 3 are 65 pins 9 which are adapted to be inserted in the welt portion of a stocking to draw the same tight over the slots after the foot portion of a stocking has been clamped in place by the clip 10. This clip is in the form of an expandable ring 11 mounted in a groove 12 in the ring 4. This clip clamps the foot portion of the stocking in place as shown in Figure 4.

I am aware of the fact that frames have heretofore been utilized in the embroidery industry to support stockings in proper coacting positions relative to needles of the embroidery machines but I am of the opinion that I am the first to provide a frame with four sets of openings each of which may be selectively brought into cooperative relation with the needles of the embroidering machines, accomplishing this desired result by arranging in spaced relation a pair of rings for giving the required circular effect 85 to the two end portions of the stocking relying on the strips 5 to hold the intermediate portion of the stocking stretched the proper degree to enable the needles to perform their proper embroidering operations. My device 90 enables the front, rear and sides of a stocking to be embroidered.

Having described my invention, what I claim is:

1. A stocking frame for embroidering machines, comprising a support adapted to be connected to the embroidering machine, a lower ring rotatably mounted on said support, an upper ring and strips connecting the rings together in spaced relation and defin- 100

ing slots equally spaced apart whereby they may be selectively aligned with the embroidering machine in the rotation of the lower ring upon said support.

5 2. A stocking frame for embroidering machines, comprising a support adapted to be connected to the embroidering machine, a lower ring rotatably mounted on said support, an upper ring and strips connecting the 10 rings together in spaced relation and defining slots equally spaced apart whereby they may be selectively aligned with the embroidering machine in the rotation of the lower ring upon said support and means for clamping 15 the lower ring in an adjusted position on the support.

3. A stocking frame for embroidering machines comprising an annular support having an attaching lug, a lower ring rotatably 20 mounted on said support, an upper ring, spaced strips rigidly connecting the rings

together and defining slots for the purpose set forth and a clamp for clamping the lower ring in any of its adjusted positions upon said support.

4. A stocking frame for embroidering machines comprising an annular support having an attaching lug, a lower ring rotatably mounted on said support, an upper ring, spaced strips rigidly connecting the rings together and defining slots for the purpose 75 set forth and a clamp for clamping the lower ring in any of its adjusted positions upon said support, pins projecting from said lower ring to engage the lower portion of a stocking mounted upon the frame and a clip removably supported by the upper ring for securing in place the upper part of the stocking when mounted upon the frame.

In testimony whereof I have signed this specification this 25 day of July 1932.

ARTHUR P. HAHNEL.
